LAMINATED WOOD WHEEL AND METHOD
OF MAKING SAME

David M. Pope, Lake Forest, and Thomas F. Spackman, Chicago, Ill., assignors of one-half to Stewart-Warner Corporation, Chicago, Ill., a corporation of Virginia, and one-half to Streator Furniture Shops, Incorporated, Streator, Ill., a corporation of Illinois

Application October 12, 1942, Serial No. 461,828

5 Claims. (Cl. 144—309)

Our invention relates to laminated wood wheels and to a method of making same.

An object of our invention is to provide a strong, inexpensive, lightweight wheel which can be easily made of readily available materials.

Another object of our invention is to provide a new and improved wheel which is durable and highly resistant to wear.

Another object of our invention is to provide a new and improved wood wheel wherein the cushioning effect increases with use and without impairing the utility of the wheel.

Another object of our invention is to provide a new and improved wood wheel which will not split or splinter.

Another object of our invention is to provide a new and improved spokeless wood wheel constructed solely of wood and resin and wherein the tensile strength of the wood is fully developed and unnecessary weight is eliminated.

Another object of our invention is to provide a new and improved wood wheel which is substantially waterproof.

Another object of our invention is to provide a new and improved method of constructing a laminated wood wheel.

Other objects and advantages will become apparent as the description proceeds.

In the drawing:

Fig. 1 is a side elevation of a laminated wood wheel embodying our invention and showing parts cut away to illustrate more clearly the manner in which the wheel is constructed;

Fig. 2 is a vertical, sectional view taken on the line 2—2 of Fig. 1; and

Fig. 3 is an enlarged, sectional view through the cushioning rim and adjacent portions of the wheel and is taken on the line 3—3 of Fig. 1.

The particular embodiment of our invention which has been selected for illustration comprises, in general, a laminated cushion rim 10, two molded laminated side plates 12 and 14, and a center axle core 16. The laminated cushion rim 10 consists of five laminations 18, 20, 22, 24 and 26 and in the particular wheel which has been chosen as a typical example of applicant's invention, each of these laminations is in the form of a ring $\frac{1}{4}$ of an inch thick. Each of these laminations or rings is constructed of eight identical segments 28 and each of these segments is arcuate and subtends an angle of 45°.

The arcuate segments 28 may be formed of poplar or any other suitable kind of wood and are so constructed that the grain of the wood in each segment points toward the outer perimeter of

the arc. Each ring is constructed by arranging eight segments in a circle and stapling together the adjacent ends of the segments, as indicated at 30 in Fig. 1, the segments being so arranged that the grain of the wood in all segments points toward the outer perimeter of the ring. The five rings thus formed are placed one upon another with the joints staggered, as indicated in Fig. 1 and with urea resin between the rings. The 5 rings are then pressed together in a hydraulic hot press so that the entire 40 segments of the five rings are virtually fused together into a single laminated rim in which all of the grain or fiber of the wood points directly outward. This 10 produces a cushion rim which is light in weight and extremely strong and durable and which will not separate into individual rings or segments when exposed to water or moisture, and the side plates 12 and 14 are of laminated construction 15 and in the particular embodiment illustrated each of these plates is composed of seven thicknesses or laminations. Each of these laminations was originally in the form of a flat, circular blank of poplar or other suitable wood $\frac{1}{20}$ of an 20 inch thick. To form one of the side plates, seven of these laminations were stacked upon each other with urea resin between each two laminations. The blanks are preferably, but not necessarily, arranged so that the wood grains in the 25 several blanks extend in different directions to provide maximum homogeneity and strength in the finished side plate.

The stack thus formed was then placed between complementary metal dies wherein the 30 centers of the dies were raised approximately $\frac{1}{16}$ of an inch higher than the outside edges of the dies. The dies were then subjected to a hydraulic pressure sufficient to create a pressure of 500 pounds per square inch on the laminations therein and simultaneously the dies and laminations were subjected to a heat of 300° F. This pressure and heat set the urea resin and permanently mold the laminated structure into a side plate having a shape conforming to that of the dies, i. e., the slightly dished shape clearly shown in Fig. 2 of the drawing.

The center axle core 16 is turned or otherwise formed from hard or other suitable wood and is coated with urea resin. The opposite sides of the 40 rim 10 are also coated with urea resin and this rim, the axle core 16, and the side plates 12 and 14 are then assembled with the axle core inside of the rim and this axle core and rim arranged between the side plates. This entire assembly is 45 then placed in a hydraulic press between metal

dies and the entire wheel pressed together under a hydraulic pressure of 500 pounds to the square inch and at a temperature of 300° F. These dies have recessed or concave faces and produce the completed assembly shown in Fig. 2, except that the assembly at this stage lacks the rivets 36.

The wheel is then bored through a spot mark placed on the side plates at the time they were molded, the bit passing through the two side plates and center core to form the axle bearing 32, clearly shown in Figs. 1 and 2 of the drawing. The wheel is then placed on a centering pin and turned slowly against high speed cutting knives which give the final finish to the wheel and make it perfectly round in relation to its axle bearing. The grease groove 34 may then be scored in the center of the axle bearing 16.

The wheel resulting from the foregoing steps is complete and entirely satisfactory for most uses. The urea resin forms a permanent waterproof bond which is stronger than the wood itself. This bond is slightly resilient and will not shatter under a blow and this resiliency permits the bond to give with the wood and retain a firm grip on the wood under all stresses and strains to which the wheel is subjected.

Our novel wheel has several advantages to which we wish to call particular attention. The rim is homogeneous and continuous and is not weakened by the pressure of spoke sockets or other interruptions to its continuity. The grain of the wood is arranged substantially radially of the rim and when this rim is subjected to considerable wear or strikes objects which would ordinarily splinter wood in its natural state, the end grains of the fibre tend to mushroom out and to remain attached to the rim. The more the rim is abused, the softer the outer part of the rim becomes without in any appreciable way losing its roundness or ability to withstand indefinitely further shocks and wear.

The side plates form strong and continuous but light supports connecting the rim with the axle core. The curvature of these side plates permits the use of a relatively long axle core with a narrow rim and provides a wide axle bearing without appreciable increase in weight. This curvature also increases the lateral strength of the side plates and of the entire wheel. The space between the rim and the core reduces weight and eliminates wood where additional strength is not needed. Our novel design fully develops the tensile strength of the wood and leaves the wheel hollow where strength is not needed or where solid wood would add little to the ability of the wheel to resist stresses developed in actual use.

The wheel shown in the drawing has been strengthened by the addition of the rivets 36 and twenty of these rivets are used in the particular embodiment selected for purposes of illustration. These rivets are inserted in holes which are drilled in the complete wheel assembly, either at the same time the bearing 32 is drilled, or in a separate operation, as desired. Washers 38 are preferably interposed between the enlarged ends of the rivets and the side plates to prevent the ends of the rivets from cutting into the side plates. While the wheel would stand up without these rivets in ordinary usage, the rivets give a double guarantee against any possible splitting of the wood and once these rivets are in place the entire assembly is tied together, irrespective of any individual failure of the resin bond or splitting of any individual piece of wood.

Where the wheel is used without rivets, it may

be painted, lacquered, varnished or finished in any other suitable manner immediately after the entire assembly has been removed from the final hot pressing operation. Where rivets are added to the wheel, such finishing operation would ordinarily be performed after the rivets had been placed in the wheel.

It is to be understood that the particular wheel selected for purposes of illustration is merely one of many possible embodiments of our invention and that the particular pressures, temperatures, thicknesses of wood, number of laminations, number of segments and type of bonding material used may be varied without departing from the scope of our invention. The kinds of woods specifically referred to are to be understood as constituting merely typical examples of various kinds of wood suitable for our purpose and the urea resin referred to is merely a typical example of a bonding material belonging to a group of thermo-setting plastics. Our invention is to be construed as including all variations and modifications falling within the scope of the appended claims.

We claim:

1. That method of constructing a laminated wood wheel which comprises cutting out a plurality of equal arcuate wooden segments, arranging said segments to form a plurality of rings, securing together the segments forming each ring, superimposing the several rings with urea resin therebetween and with the joints between the segments of each ring offset from the joints between the segments of all the other rings, subjecting the stack of rings thus formed to pressure and heat to mold said rings into a permanent rim, cutting out a plurality of circular, flat blanks of wood, placing a plurality of said blanks upon each other with urea resin therebetween, subjecting said blanks to pressure and heat and simultaneously offsetting the central portion of said blanks to form a permanent molded side plate, forming an axle core of wood, assembling said core and rim in spaced relation between a pair of said side plates and with urea resin between said side plates and the contacting surfaces of said rim and core, subjecting the assembly thus formed to heat and pressure to set said urea resin and thereby form a permanently bonded wheel, forming a bearing in said side plates and core, and inserting reinforcing rivets through said plates and rim.

2. That method of constructing a laminated wood wheel which comprises cutting out a plurality of equal arcuate wooden segments, arranging said segments to form a plurality of rings, securing together the segments forming each ring, superimposing the several rings with thermo-setting resin therebetween and with the joints between the segments of each ring offset from the joints between the segments of all the other rings, subjecting the stack of rings thus formed to pressure and heat to mold said rings into a permanent rim, cutting out a plurality of circular, flat blanks of wood, placing a plurality of said blanks upon each other with thermo-setting resin therebetween, subjecting said blanks to pressure and heat and simultaneously offsetting the central portion of said blanks to form a permanent molded side plate, forming an axle core of wood, assembling said core and rim in spaced relation between a pair of said side plates and with thermo-setting resin between said side plates and the contacting surfaces of said rim and core, subjecting the assembly thus formed to

heat and pressure to set said thermo-setting resin and thereby form a permanently bonded wheel, and forming a bearing in said side plates and core.

3. That method of constructing a laminated wood wheel which comprises cutting out a plurality of equal arcuate wooden segments, arranging said segments to form a plurality of rings securing together the segments forming each ring, superimposing the several rings with urea resin therebetween and with the joints between the segments of each ring offset from the joints between the segments of all the other rings, subjecting the stack of rings thus formed to pressure and heat to mold said rings into a permanent rim, cutting out a plurality of circular, flat blanks of wood, placing a plurality of said blanks upon each other with urea resin therebetween, subjecting said blanks to pressure and heat and simultaneously offsetting the central portion of said blanks to form a permanent molded side plate, forming an axle core of wood, assembling said core and rim in spaced relation between a pair of side plates and with urea resin between said side plates and the contacting surfaces of said rim and core, subjecting the assembly thus formed to heat and pressure to set said urea resin and thereby form a permanently bonded wheel.

4. That method of constructing a laminated wood wheel which comprises cutting out a plurality of equal arcuate wooden segments, arranging said segments to form a plurality of rings securing together the segments forming each ring, superimposing the several rings with urea resin therebetween, subjecting the stack of rings thus formed to pressure and heat to mold said rings into a permanent rim, cutting out a plurality of circular, flat blanks of wood, placing a plurality

of said blanks upon each other with urea resin therebetween, subjecting said blanks to pressure and heat to form a permanent molded side plate, forming an axle core of wood, assembling said core and rim in spaced relation between a pair of side plates and with urea resin between said side plates and the contacting surfaces of said rim and core, subjecting the assembly thus formed to heat and pressure to set said urea resin and thereby form a permanently bonded wheel, forming a bearing in said side plates and core, and inserting reinforcing rivets through said plates and rim.

5. That method of constructing a laminated wood wheel which comprises cutting out a plurality of equal arcuate wooden segments, arranging said segments to form a plurality of rings securing together the segments forming each ring, superimposing the several rings with urea resin therebetween and with the joints between the segments of each ring offset from the joints between the segments of all the other rings, subjecting the stack of rings thus formed to pressure and heat to mold said rings into a permanent rim, cutting out a plurality of circular, flat blanks of wood, placing a plurality of said blanks upon each other with urea resin therebetween, subjecting said blanks to pressure and heat and simultaneously offsetting the central portion of said blanks to form a permanent molded side plate, assembling said rim between a pair of said side plates and with urea resin between said side plates and the contacting surfaces of said rim, and subjecting the assembly thus formed to heat and pressure to set said urea resin and thereby form a permanently bonded wheel.
